UNITED STATES PATENT OFFICE

165,047

COMBINED TABLE ORNAMENT AND STATUARY BOX

Jack Barofsky, Los Angeles, Calif.

Application September 14, 1948, Serial No. 148,575

Term of patent 14 years

(Cl. D29—23)

To all whom it may concern:

Be it known that I, Jack Barofsky, a citizen of the United States, residing at Los Angeles, in the county of Los Angeles, and State of California, have invented a new, original, and ornamental Design for a Combined Table Ornament and Statuary Box of which the following is a specification, reference being had to the accompanying drawings, forming part thereof.

Figure 1 is a front perspective view of a combined table ornament and statuary box, showing my new design.

Figure 2 is a fragmentary front perspective view thereof with the top portion of the article raised.

Figure 3 is a side elevational view thereof.

Figure 4 is a top plan view thereof, with the cover removed.

The side opposite that shown in Fig. 1 of the drawing is the same as the side illustrated and the back is plain.

The dominant features of my design are shown in solid lines in the drawings.

This is a continuation-in-part of my application Serial Number D. 136,805 filed Feb. 10, 1947, which is now abandoned.

I claim:

The ornamental design for a combined table ornament and statuary box, as shown and described.

JACK BAROFSKY.
